UNITED STATES PATENT OFFICE

JOSEPH V. ROBINSON, OF NEW YORK, N. Y.

AUTOMATIC TRAIN-PIPE CONNECTER

Application filed December 4, 1919, Serial No. 342,456. Renewed November 10, 1928.

My invention relates to automatic train pipe connectors and has for its object to provide an improved support for such connectors in which free universal movement of the coupling head will be allowed with the minimum of resistance to such movement, and in which the universal support of my improvement may be shifted longitudinally of the car independent of movement of the upper part of the supporting bracket. A further object of my invention is to provide an improved supporting bracket for automatic train pipe connectors which will be simple and efficient, and economical of manufacture. And still another object of my invention is to provide improved means for positively locking the bracket to the lug of a car coupler and for correctly positioning the bracket with respect to the lug.

My improvement consists of the combinations, arrangements, and constructions described in the following specifications, pointed out in the annexed claims, and illustrated in the accompanying drawings, in which

Figure 1 is a longitudinal elevation of my improved support, showing some of the parts in section.

Figure 2 is a longitudinal plan view of my improvement with some of the parts in section.

Figure 3 is a detail of the upper part of the bracket of my improved support showing in elevation the connection between the members thereof, and

Figure 4 is an elevation of my improved support taken on the line 4—4 of Figure 1, and showing some of the parts in section.

Referring now to the drawings: My improved support consists of a bracket A having a pair of ears 5 and 6 adapted to be securely clamped, as by means of bolts 7, to opposite sides of a lug 8 of the car coupler 9. Each ear is provided with a seat or way 10 between which and the underside 11 of the lug 8 a tapered wedge 12 is driven. The forward end 13 of the seats 10 is curved upwardly to deflect the course of the forward end 14 of the wedge 12 as the wedge is driven home. This construction forces the forward

end of the wedge upwardly around the corner 15 on the front face of the lug 8 and thus positively locks the wedge in position. It will be observed that the seats 10 and the wedge 12 are tapered, so that, as the wedge is driven home, the ears 5 and 6 are drawn tightly down upon the bolts 7 and are squared with respect to the lower face 16 of the lug. This construction efficiently prevents back lash of the bracket A, and insures that at all times the bracket will be properly positioned with respect to the lug 8. Any wear upon the mating parts of the bracket and the lug is effectively taken up by driving the wedge 12 forward.

Each of the ears 5 and 6 have formed integrally with it a perforated boss or seat 17 adapted to adjustably receive the upper ends 18 of the base 19 of the bracket A. The base consists of a bar of iron, preferably cylindrical in cross section, formed into a U shaped member as shown, the upper ends 18 of which are disposed at substantially a right angle to the vertical walls thereof and are adjustably mounted in the seats 17 on the ears 12. These ends 18 are threaded to receive nuts 21 whereby the base 19 may be shifted longitudinally of the car independent of movement of the ears 12.

Between the vertically extending walls or sides of the U shaped base 19 I mount a shank or hollow body member B, comprising a laterally diverging fluid conduit 22 and a vertically extending flange or projection 23, the conduit being at the forward end of the body and the flange at the rear end thereof and the flange and the conduit being connected by spaced walls or straps 24 preferably formed integrally with the conduit and the flange. The space between the straps 24 forms in effect a slot extending through the pipe or member B. The lower end 25 of the base 19 lies in the horizontal plane and extends transversely of said hollow body and projects through the opening therein. Upon this portion 25 of the base 19 I pivotally mount a pivot bar on tie rod 26 the same having a perforated head 27 which embraces the lower end 25 of the base and lies between the straps 24 and within the hol-

low of the body B, as shown. The tie rod extends rearwardly of said body through an opening 28 in the flange 29, and threadingly receives at its rear end a member or abutment 30 adapted to be manually adjusted along the pivot bar 26 for a considerable distance. Between this nut and the rear face of the flange 29 I mount a suitable buffer spring C. The spring surrounds the tie rod 26 and rests on a seat 31 formed therefor upon the rear face of the flange 29, and operates to maintain the flange normally in contact with the rear face of the base 19 with the body B normally disposed in the horizontal plane. Any desired tension of the spring C may be had by adjusting the nut 30, which operation will vary the force required to shift the body B from its normal uncoupled position, either longitudinally of the car or laterally thereof. Any suitable form of coupling head D may be used with my improved support and may, in any satisfactory manner, be mounted upon the body B. I preferably threadingly mount the head upon the forward end of conduit 22, and provide with a port 32 and gasket 33 both of which have communication with the conduit 22.

To direct the fluid from the train pipe of the car to the connector, any satisfactory form of connection may be used. I show the usual section of air hose now universally in use upon railway cars, the flexible metallic pipe may be employed for this purpose if desired.

It will be observed that the flange 23 contacts with the base 19 only at the sides of the base and the flange, there being no contact between the flange and the base between the vertical walls of the latter. While the base 19 and the head 27 of the tie rod may be formed of any desired shape in cross section, as for instance rectangular, I preferably form them round. This construction produces a universal joint in which the curved faces of the mating members permit easy pivotal movement between them in all directions.

In assembling my improved support the head 27 of the tie rod 26 is passed over one end 18 of the base 19 and is then shifted to position on the base. Thereafter the base is hooked into the hollow body B by passing one end of the base through the body from a side thereof after which the ears 12 are assembled on the ends 18 of the base. The spring C is then passed over the tie rod 26 and positioned on the seat or lower end 25 of the base whereupon the nut 30 is applied and adjusted to place the spring placed under sufficient tension to properly support the coupling head D. This construction produces a highly efficient support, which will permit free universal movement to the coupling head D with the minimum resistance to

such movement, and which may be adjusted longitudinally of the car coupler to compensate for wear upon the car coupler knuckle, or upon the parts of my improvement, and thus maintain a substantially constant degree of compression of the spring C at all times. Through contact of the straps 24 of the body B with the base 19 undue rotation of the coupling head and body B about their longitudinal axis is prevented.

Variations may be made in my improvement within the scope of my invention; I do not therefore desire to be limited to the exact construction disclosed.

What I claim as new and desire to secure by Letters Patent of the United States, is

1. In an automatic train pipe connector, the combination of a coupling head, a hollow body connected therewith, a lug, a universal support for said head comprising connected members one of which extends vertically of said head and carries a rigid portion which extends transversely of the head into the opening of said body, and the other of which is pivotally mounted upon said transversely extending portion, and means for connecting said vertically extending member to said lug.

2. In an automatic train pipe connector, the combination of a car coupler having a lug, a member connected with said lug, a coupling head, a hollow body connected with said head and extending rearwardly thereof, a base extending downwardly from said member and connected therewith a seat rigidly connected to said base and extending transversely thereof into the hollow of said body, a member mounted upon said seat for universal movement, and a spring acting against said body to extend said coupling head.

3. In an automatic train pipe connector, the combination of a car coupler having a lug, a coupling head, a hollow body connected with said head, a universal support for said head comprising pivotally connected members one of which members includes two portions rigidly connected together, one portion extending through the hollow of said body and the other portion extending vertically towards said lug and the other of which members extends from out of the hollow of said body axially of the body and to the rear thereof, an abutment upon said rearwardly extending member, a spring interposed between said abutment and said body for projecting said head, and means for connecting the vertically extending member to said lug.

4. In an automatic train pipe connector, the combination of a coupling head, a bracket, a universal joint on said bracket for permitting universal movement of said head, said joint comprising mating members one of which is rigid with said bracket, a projection resting normally against the rear side of said bracket, spaced means connecting said head

with said projection, said spaced means being arranged one above the other and being positioned above and below said universal joint, and a spring for projecting said coupling head.

5. In an automatic train pipe connector, the combination of a coupling head, a perforated flange, means connecting said head with said flange, and a universal support for said head comprising pivotally associated members one of which is U-shaped and lies in front of said flange with its rear side contacting with said flange and the other of which is mounted upon the bottom of said U-shaped portion and extends rearwardly thereof past said flange, and resilient means for extending said head.

6. In an automatic train pipe connector, the combination of a coupling head, a flange, mechanism connecting said head with said flange, a bracket comprising spaced portions which engage the sides of said flange, the upper central portion of said flange being free from contact with said bracket, means lying in front of said flange and rigidly connected to the spaced members of said bracket, a member pivotally mounted upon said means, and means for flexibly maintaining said flange and said bracket in engagement, with said coupling head horizontally disposed.

7. In an automatic train pipe connector, the combination of a coupling head, a flange, means connecting said head with said flange, a bracket engaging one side of said flange, a universal joint comprising pivotally connected members one of which extends transversely of said bracket and the other of which projects rearwardly of the bracket, and a spring acting upon said flange and said universal joint to resist vertical movement of said coupling head, said flange and said bracket being so related that said spring resists downward movement of said coupling head from the normal uncoupled position but not upward movement thereof from said position.

8. In an automatic train pipe connector, the combination with a coupling head, of a universal support therefor comprising connected members one of which is U-shaped and the other of which is pivotally mounted upon the bottom of said U-shaped member.

9. In an automatic train pipe connector, the combination with a car coupler having a lug, of a coupling head and a support therefor, said support comprising a U-shaped bracket the upper end of which is connected to said lug and the lower end of which carries a universal joint the members of which joint are pivotally connected.

10. In an automatic train pipe connector, the combination of a coupling head, a lug, and a support for said head comprising a U-shaped member the lower end of which car-

ries a universal joint, a pair of ears one of which is mounted on one fork of said U and the other of which is mounted on the other fork thereof, and means for connecting said ears with said lug.

11. In an automatic train pipe connector, the combination of a car coupler having a lug, a coupling head, and a universal support for said head comprising a pair of ears connected to said lug in opposite sides thereof, and a U-shaped member the upper ends of which are connected with said ears and the lower end of which carries a universal joint.

12. In an automatic train pipe connector, the combination of a support comprising a lug, a pair of ears connected with said lug on opposite sides thereof, each of said ears being provided with an opening, a U-shaped base the lower end of which carries a universal joint and the upper end of which extends into said openings and is connected with said ears, and a coupling head connected with said base and adapted to move universally upon the lower end thereof.

13. In an automatic train pipe connector, the combination of a car coupler having a lug, a coupling head, and a suitable support therefor comprising a pair of ears connected to said lug, each of said ears being provided with an opening, a vertically extending base comprising spaced members the upper ends of which are disposed at an angle to the vertical plane and extend into the openings in said ears, and means for securing said members in said openings.

14. In an automatic train pipe connector, the combination of a car coupler having a lug, a coupling head, and a suitable support therefor comprising a pair of ears connected to said lug, each of said ears being provided with an opening, a vertically extending base comprising spaced members the upper ends of which are disposed at an angle to the vertical plane and extend into the openings in said ears, and means for adjustably securing said members in said openings.

15. In an automatic train pipe connector, the combination with a car coupler having a lug, of a coupling head and a support therefor, said support comprising independent members connected with said lug, a vertically extending base connected with said members, a universal joint at the lower end of said base, and means for adjusting said base along said members to shift said universal joint axially of said car coupler.

16. In an automatic train pipe connector, the combination with a car coupler having a lug, of a coupling head, a support therefor, support comprising independent members clamped to opposite sides of said lug and having a bearing extending axially of said car coupler, a U-shaped base the upper ends of which terminate in horizontally disposed projections which extend into said bearings,

and means carried by said projections for shifting said base axially of said car coupler.

17. In an automatic train pipe connector, the combination of a lug, a coupling head, a hollow body connected at one end with said head and at the other end terminating in a flange, and a U shaped base extending through the opening in said hollow body and thence upwardly towards said lug, the upper ends of said base being disposed horizontally and connected with said lug.

18. In an automatic train pipe connector, the combination of a coupling head, a hollow body connected with said head and having a perforated flange, a base having a rigid horizontally arranged portion at its lower end, a member pivotally mounted upon said rigid portion of said base within the opening in said body and extending rearwardly of the body through said flange, a seat upon said flange, a spring surrounding said member and bearing upon said seat to project said coupling head, and means adjustably mounted upon the rear end of said member for varying the tension of said spring.

19. In an automatic train pipe connector, the combination with a car coupler having a lug, of a pair of ears clamped to said lug one on one side of the lug and one on the other, a horizontally disposed bearing on each of said ears, a seat on one of said ears, a device interposed between the lower side of said lug and said seat to securely lock the ears in position a coupling head, a fluid conduit connected with said head, a flange, means connecting said conduit with said flange, a U shaped base the upper end of which terminates in horizontally disposed projections which extend into the bearings of said ears, a universal joint carried at the lower end of said base one member of which joint extends rearwardly through said flange, means for adjusting said base relative to said ears to shift said universal joint axially of said car coupler, a spring surrounding said rearwardly extending member of said joint and bearing upon said flange for extending said coupling head, and an abutment adapted to be manually adjusted along said rearwardly extending member of said joint to vary the tension of said spring against said flange.

20. In an automatic train pipe connector, the combination of a coupling head, a bracket having a seat, a member connected with said head and extending rearwardly past said bracket, said member being provided with an elongated opening, a tie rod pivotally mounted on the seat of said bracket and extending rearwardly of the latter, a horizontally arranged portion rigid with said bracket and extending transversely thereof through the opening in said member with the ends thereof projecting laterally beyond said member, a coiled spring surrounding said tie rod and

yieldingly sustaining said coupling head with the rear end of said member engaging said bracket, and means to secure said spring in place.

21. In an automatic train pipe connector, in combination, a bracket having a rigid horizontally arranged portion provided with a seat on its front face, a coupling head, a member connected to said head and extending rearwardly past said bracket and having a perforated flange adapted to bear against the rear face of the bracket, a tie rod engaging said seat and extending rearwardly through said perforation, and a spring surrounding said tie rod for pressing said flange against the bracket.

22. In a train pipe connector, a bracket having spaced portions at its lower end, a member extending between said spaced portions of the bracket and rigidly secured thereto at its ends, a coupling head having a shank extending rearwardly past said member and said bracket and provided with a projection adapted to contact with the rear face of the bracket, said shank having two spaced portions arranged on opposite sides of said member, a device pivotally engaging said member, and a spring for holding said device against said member and said projection against the bracket.

23. In a train pipe connector, a bracket having spaced portions at its lower end, a member extending between said spaced portions of the bracket and rigidly secured thereto at its ends, said member being arranged substantially horizontally and having a seat intermediate its ends, a coupling head, a rearwardly extending shank secured thereto and provided with a projection for engaging the rear face of the bracket, said shank comprising upper and lower portions between which said member is arranged, a device pivotally engaging said seat and means for yieldingly holding said device in said seat and said projection against the bracket.

24. In a train pipe connector, a bracket having spaced portions at its lower end, a substantially horizontal part rigidly secured to said spaced portions and extending between the same, a coupling head, a rearwardly extending shank secured thereto and provided with a projection for engaging the rear face of the bracket, said shank having spaced portions arranged respectively above and below said horizontal part, a device pivotally engaging said horizontal part, and a spring for yieldingly holding said device and said projection against the bracket.

25. In a train pipe connector, a bracket having spaced portions at its lower end, a substantially horizontal part rigidly secured at its ends to said spaced portions and extending between the same, a coupling head, a rearwardly extending shank secured thereto and provided with a projection for engaging

the rear face of the bracket, said shank having a slot through which said horizontal part extends, a bar pivotally engaging said horizontal part intermediate its ends and extending rearwardly of the bracket and having an abutment, and a spring surrounding said bar and engaging said abutment and projection.

26. In a train pipe connector, a bracket having spaced portions at its lower end, a member extending between said spaced portions of the bracket and rigidly secured thereto at its ends, a coupling head having a shank extending rearwardly past said member and said bracket and provided with a projection adapted to contact with the rear face of the bracket, said shank having a portion arranged on each side of said member with the ends of said member extending laterally beyond the sides of said shank, a device pivotally engaging said member between the spaced portions of said shank, and a spring for holding said device against said member and said projection against the bracket.

In testimony whereof I hereby affix my
25 signature.

JOSEPH V. ROBINSON.
